UNITED STATES PATENT OFFICE

165,755

TUMBLER OR SIMILAR ARTICLE

Willard R. Horne, New York, N. Y., assignor to
Corning Glass Works, Corning, N. Y., a corpo-
ration of New York

Application January 23, 1951, Serial No. 13,919

Term of patent 7 years

(Cl. D36—8)

To all whom it may concern:

Be it known that I, Willard R. Horne, a citizen of the United States of America, residing at New York, in the county of New York and State of New York, have invented a new, original, and ornamental Design for a Tumbler or Similar Article, of which the following is a specification, reference being had to the accompanying drawing, forming a part thereof.

Figure 1 is a side elevational view of a tumbler embodying my new design.

Figure 2 is a developed view of the side wall of the tumbler.

I claim:

The ornamental design for a tumbler or similar article, substantially as shown.

WILLARD R. HORNE.
